UNITED STATES PATENT OFFICE.

ANDREW ANDERSON, OF DETROIT, MICHIGAN.

MATCH-MACHINE.

SPECIFICATION forming part of Letters Patent No. 637,064, dated November 14, 1899.

Application filed February 23, 1899. Serial No. 706,523. (No model.)

To all whom it may concern:

Be it known that I, ANDREW ANDERSON, a citizen of the United States, residing at Detroit, in the county of Wayne and State of Michigan, have invented certain new and useful Improvements in Match-Machines, of which the following is a specification, reference being had therein to the accompanying drawings.

10 My invention relates to match-machines of that class in which the process of forming the matches is carried on automatically and continuously from start to finish.

The invention consists in the means employed for assorting the splints and eliminating the broken ones and the dust and dirt therefrom and the remaining splints into parallel arrangement; further, in the means for separating and transferring from the bunch 15 or pile of parallel splints a group of splints spaced from each other and for engaging said spaced group with an endless carrier, and, further, in the peculiar construction, arrangement, and combination of parts, as more fully 20 hereinafter described and claimed.

In the drawings, Figure 1 is a vertical central longitudinal section through my machine. Fig. 2 is a cross-section on line xx . Fig. 3 is a sectional perspective view of the grouping and transfer mechanism. Fig. 4 is a section similar to Fig. 3, showing the parts in a different position. Fig. 5 is a section on line yy , Fig. 4. Fig. 6 is a front elevation of a section of the endless carrier. Fig. 7 is a 35 perspective view of one of the carrier-links. Fig. 8 is a central longitudinal section thereof. Fig. 9 is a horizontal section on line zz , Fig. 1.

The process which is carried out by my machine consists of the following steps: The splints having been first formed are fed in an irregular mass mixed with the broken fragments and more or less dust, dirt, slivers, &c., into the assorting device, in which the debris is 40 eliminated and the remaining good splints are arranged in parallelism. The next step is the transferring of said parallelly-arranged splints to an endless carrier and engaging them therewith in spaced groups, said carrier holding the splints during the process of 45 forming the heads, and finally the disengag-

ment of the completed matches from the carrier.

The mechanism for assorting the splints comprises the box or receptacle A, longitudinally secured upon the supporting-frame B and provided with means for imparting to it a rapid oscillatory movement, such as the eccentric C on the rotary shaft D, connected by the rod E to said receptacle. The bottom of 50 the receptacle is formed of a grating F, comprising the separated cross-slats a and the parallel longitudinal division-strips b above said slats, the latter being separated from each other by a space which is less than the 55 length of a splint. The grating F is slightly inclined and at its lower end connects with a vertical trunk G, a similar oppositely-inclined grating H being arranged on the opposite side of the trunk.

70 c is a partition which divides the receptacle A into two compartments, said partition extending down to the top of the longitudinal strips b . The trunk G is divided longitudinally by partitions d , corresponding to strips 75 b , into a number of parallel passage-ways, the width of each being less and the length slightly more than the length of the splints. The upper end of the trunk has a hinge connection with the receptacle, and the lower end 80 connects with a stationary trunk-section I.

M is the endless carrier, which is formed of a series of splint-holding cross-bars linked together, so as to constitute a chain. This carrier is of a suitable length and is suitably arranged to carry the splints during the entire process of forming the heads of the matches and of drying them after formed; but in the drawings I have shown only a short section of the carrier passing around in rear of the 85 trunk G. Each holder or link of the carrier comprises two parallel rods $e e'$, round in cross-section and spaced a proper distance apart to form between a narrow slit, into which the ends of the splints may be wedged. 90 I preferably form those rods of gas-pipe and connect them together at their ends by the links f , which have the pins or nipples g extending into the ends of said pipes and secured therein by the pins or rivets f' , passing 95 centrally through said nipple and pipes. These rivets also secure in place spacing 100

blocks or washers g' , placed between the pipes $e e'$, and to secure greater rigidity I preferably connect the rods $e e'$ together at their longitudinal center by another pin or rivet, 5 with a spacing-washer g^2 between. The rods or pipes $e e'$ are preferably flattened slightly on their adjacent sides to form parallel surfaces, between which the splints are inserted. Each link f is bifurcated at one end and at 10 its opposite end is provided with a tongue h , adapted to form a knuckle with the bifurcated end of the adjoining link, to which it is pivotally secured by the pin h' . Each link f is also provided with the outwardly-extending 15 lug i .

In rear of the feed-trunk G the carrier M passes through suitable grooved guides N , which engage with the lugs i on opposite sides of the carrier and hold it from lateral movement. 20 The guides N are secured to the frame B , which also forms a support for the transfer mechanism, by means of which the splints are taken from the trunk and engaged with the holder-links of the carrier. The construction 25 of this transfer mechanism is as follows:

O is a channeled plate extending across beneath the stationary trunk I , the channels in said plate being arranged parallel to the splints in the trunk and each being of a size to 30 receive a single splint only. The partitions O' between the channels are of the proper thickness to give the desired spacing to the splints and preferably extend out in rear of the holder into proximity to the carrier M , 35 one link of which is in a position to bring the slot between its rods $e e'$ in line with said channels.

$P P$ are plungers in the channels of the plate O , which are normally retracted from 40 that portion of the channels directly beneath the trunk, but are adapted to be moved rearward to force the splints out through said channels into engagement with the carrier. These plungers are preferably connected to a 45 common head or cross-bar P' , which is secured at its opposite ends to the slides P^2 , the latter being adapted to be reciprocated by cams Q on the shaft Q' .

Above the plate O is arranged an agitator 50 comprising a frame R and a series of wings or thin cross-partitions R' . This frame is oscillated by means of a suitable connection, such as the eccentric-rod R^2 , connected to an eccentric on the rotary shaft R^3 , the arrangement being such that the oscillation of the frame will cause the wings R' to move the splints laterally across the plate O , and thereby fill the channels with splints, while the movement of the plungers P will, as before 55 stated, force said splints out of said channels and into engagement with the carrier M .

The splints in the channels are held from lateral displacement after passing out from beneath the trunk I by the rearward extensions of the partitions O' , which are of sufficient length to remain between said splints after the latter have been engaged with the

carrier. These partitions do not, however, interfere with the subsequent movement of the carrier, as the direction of its travel is downward in a substantially vertical plane; but the space immediately below the splints when thus engaged with the carrier must of necessity be clear of obstruction during the interval in which the carrier moves, as otherwise 70 the splints would not be free to move with said carrier. At the same time in order to insure the proper engagement of the splints with the carrier they must be held from vertical as well as lateral displacement until 80 they are firmly clamped between the bar $e e'$. To accomplish this result, I provide a laterally-movable bed forming the base of the channels in the plate O , which bed is normally clear of the path of the splints carried 85 by the carrier, but which during the rearward movement of the plungers also travels rearward and supports the splints until firmly engaged. This bed may, if desired, be formed of a single plate; but as that would necessitate reducing the thickness of the plate O to the diameter of a splint I preferably form the bed of a series of bars S , slidingly secured in the channels of the plate O beneath the plungers P . The bars S are positively actuated both in their rearward movement and when returned again to their normal positions, preferably by providing the plungers P with downwardly-extending lugs k , engaging with shoulders l , formed in said bars S . 90 These shoulders l are a sufficient distance apart to permit of a lost motion or a differential movement of the plungers P and bars S , as the former must travel a distance greater than the length of the splint and the latter 95 need only move far enough to support the splint while being engaged with the carrier. The lesser movement of the bars S is also a necessity, as they would otherwise strike against the carrier before the splint could be 100 engaged therewith.

To prevent possibility of the plungers P and bed-bars S getting out of line, I preferably make the channels in the plate O of dovetail shape or larger at the bottom and 115 tapering toward the top. The plungers and bars are of a corresponding opposite taper, and thus are held from rising in the channels.

The carrier M is given an intermittent movement while in the guideways N by means of cams T on opposite sides thereof, preferably arranged just below the transfer mechanism. These cams have grooves or threads, with which the lugs i on the links f engage, a portion of these threads being spiral to cause 120 the downward movement of the carrier, while another portion is in a plane at right angles to the axis which holds the carrier stationary while the transfer mechanism engages the splints therewith. Each link of the carrier 130 is thus held absolutely in line with the splints in the channeled plate O while the transfer mechanism is in operation and is then moved downward and another link brought into its

place before the next operation of said mechanism. The cams T are mounted upon shafts T', which have any suitable drive connection with the other parts of the mechanism properly timed to cause the operation of parts in the proper sequence.

The main portion of the carrier M (not shown) may be given either an intermittent or a continuous movement. In the latter case sufficient slack must be given between it and the portion in the guides N to permit of the intermittent movement of said portion.

Above the transfer mechanism is arranged the knocking-out mechanism for detaching the finished matches from the carrier. This preferably comprises a sliding plate U, which is intermittently reciprocated by levers U', actuated by cams U² on the shaft Q', and presses the matches out from the slot between the bars e and e', allowing them to fall on a transversely-moving carrier V, which removes them from the machine.

Below the transfer mechanism I preferably arrange the sliding bar W, which is pressed against the splints already in engagement with the carrier and evens their ends.

In the operation of the machine as a whole the splints are first fed into the receptacle A behind the partition c and in the rapid oscillation of said receptacle arrange themselves in parallel relation, dropping into the channels between the strips b, and, passing under the portion c, travel down the inclined grating toward the trunk G. In passing down this grating the broken splints and all foreign matter will drop through between the bars a, so that only the good splints will reach the trunk G. Should any of the splints be thrown by the oscillation of the receptacle across the opening into the trunk G, they would land on the oppositely-inclined grating H and be fed back again into said trunk. The trunk G having been once filled with splints arranged in parallelism, the splints as they come from the grating F will keep the trunk constantly full, while the oscillation of the trunk will cause the splints therein to feed downward. At the same time motion being imparted to the agitating-frame R and to the plungers P will, as before described, fill the channels and cause the transfer of the splints from the bottom of the trunk to the carrier M, properly spaced to leave room for the formation of the heads. The splints thus in engagement with the carrier will be carried thereby during the entire process of forming the heads and finally removed by the reciprocating plate U just before they have completed the circuit of the carrier.

60. What I claim as my invention is—

1. In a match-machine, the combination with a splint-carrier, of a splint-holder, a rigid guide extending out from the side of said holder toward the carrier having a series of parallel channels therein, adapted to receive the splints, a plunger for forcing the splints out through said channels into engagement

with said carrier, a bed forming the bottom of such channels on which said splints rest, and means for moving said bed outward to support the splints while being engaged with the carrier and subsequently retracting said bed to be out of the path of said splints in the movement of the carrier.

2. A match-machine comprising a reciprocating splint-receptacle adapted to arrange the splints in parallelism longitudinally thereof, a downwardly-extending feed-trunk connected with said receptacle adapted to be oscillated therewith at its upper end and stationary at its lower end, an endless carrier having a section thereof parallel to said feed-trunk at its lower end and adapted to be intermittently actuated, and transfer mechanism for removing a series of spaced splints from the lower end of said trunk and engaging them with said carrier.

3. In a match-machine a reciprocating splint-receptacle having a downwardly-extending trunk connected therewith, a grated bottom to said receptacle inclining downward toward said trunk and comprising cross-slats and longitudinally-extending division-strips thereabove spaced from each other by less than the length of a splint, and a similarly-formed oppositely-inclined grating on the opposite side of said trunk.

4. In a match-machine an endless splint-carrier comprising a series of splint-holders, each consisting of a pair of rods arranged parallel to each other with a slight space between and links connecting said rods rigidly together and adapted to be pivotally connected to the links of the adjacent holders, a spacing block or washer between the central portion of said rods and a pin or rivet passing through said rods and block.

5. In a match-machine an endless splint-carrier comprising a series of splint-holders, each consisting of a pair of tubular rods arranged parallel to each other with a slight space between, end links having inwardly-projecting lugs or pintles engaging with the ends of said tubes and pivotally connected with the links of the adjacent holder, spacing blocks or washers between the ends of said rods adjacent to said links and securing pins passing through said tubular rods, pintles and spacing-blocks.

6. In a match-machine, the combination of a splint-holder provided with a bottom plate having a series of parallel channels therein, a series of reciprocating plungers in said channels and a bed comprising a series of bars in said channels beneath said plungers and adapted to be reciprocated thereby.

7. In a match-machine, the combination of a splint-holder provided with a bottom plate having a series of parallel channels formed therein, a series of reciprocating plungers in said channels, a bed comprising a series of bars in said channels, beneath said plungers and a lost-motion connection between said plungers and bars.

8. In a match-machine the combination with the splint-holder provided with a bottom plate having a series of parallel dovetail channels therein, of reciprocating plunger 5 and bed bars in said channels tapered to fit within said channels for the purpose described.

In testimony whereof I affix my signature in presence of two witnesses.

ANDREW ANDERSON.
